UNITED STATES PATENT OFFICE.

HANS PETERSON, OF MORA, MINNESOTA.

POTATO-GRADER.

962,048.

Specification of Letters Patent. Patented June 21, 1910.

Application filed September 27, 1909. Serial No. 519,819.

To all whom it may concern:

Be it known that I, HANS PETERSON, a citizen of the United States, residing at Mora, in the county of Kanabec and State of Minnesota, have invented certain new and useful Improvements in Potato-Graders; and I do hereby declare the following to be a full, clear, and exact description of the invention, such as will enable others skilled 10 in the art to which it appertains to make and use the same.

This invention relates to rotary screens for sorting vegetables and fruit; and it consists in the novel construction and combination of the parts hereinafter fully described and claimed.

In the drawings, Figure 1 is a longitudinal section through a screen constructed according to this invention. Fig. 2 is an end 20 view of the screen. Fig. 3 is a diagram of the screening cylinders.

A is a supporting frame of any approved construction provided with bearings *b* at its ends.

25 B is a shaft arranged in a substantially horizontal position and journaled in the bearings *b*. This shaft is provided at one end with a crank-handle *b'* or any other suitable driving device for revolving it.

30 C, D, and E, are three screening cylinders arranged one inside the other and secured to the shaft B by arms *f*. These cylinders are formed of crossed wires, and the periphery of each cylinder is corrugated spirally to 35 form screwthreads. Each screen has screw-threads which cover its entire surface, and the screwthreads are preferably of double pitch so as to have greater angularity than single-pitch screwthreads. The inner and 40 smallest cylinder C has the largest spaces between its wires, and its screwthreads *c* are arranged in the same direction as the screwthreads *d* of the intermediate cylinder D which has smaller spaces between its 45 wires. The outer cylinder E has its screw-threads *e* arranged in the reverse direction from the screwthreads *c* and *d*, and its wires form space of still smaller size.

G is the inlet hopper into which the potatoes are placed and which discharges them 50 into one end of the smallest screening cylinder C. The screwthreads *c* cause the largest potatoes to move longitudinally of the screen and pass out by the discharge chute

55 *g* at the other end of it from the hopper G.

The potatoes which fall through the

screening cylinder C are caught by the intermediate screening cylinder D and are moved longitudinally by its screwthreads, the potatoes of intermediate size being discharged down a chute *h* arranged under the chute *g*. The potatoes which fall through the cylinder D are caught by the outer cylinder E and are moved longitudinally by its screwthreads *e*. The smallest potatoes are 60 discharged from the cylinder E down a chute *i* arranged under the inlet hopper G, and the dirt falls through the wires of the largest screen E.

By making one of the screening cylinders 70 with its screwthreads in the opposite direction from the screwthreads of the other two cylinders, the machine can be made shorter and more effective than if the screwthreads all ran in the same direction; and as the potatoes are discharged at opposite ends of 75 the machine there is more room for the discharge chutes and receiving receptacles. By making the two inner cylinders with screw-threads of the same direction the potatoes 80 discharged from them can be received in separate receptacles, or they can be received in a single receptacle when it is desirable to separate the potatoes into two grades only, and remove the smallest from 85 them.

What I claim is:

1. In a grader, the combination, with a supporting frame, of a shaft journaled in the said frame and provided with supports, 90 and three screening cylinders of different diameter secured to the said supports and having their peripheries corrugated to form spiral screwthreads, one of the said cylinders having its screwthreads arranged in the 95 opposite direction from the screwthreads of the other two cylinders.

2. In a grader, the combination, with a supporting frame, of three revoluble screening cylinders of different diameter mounted 100 in the frame one inside the other and having their peripheries corrugated to form spiral screwthreads, the outer cylinder having its screwthreads arranged in the opposite direction from the screwthreads of the other two 105 cylinders.

In testimony whereof I have affixed my signature in the presence of two witnesses.

HANS PETERSON.
